Patented Oct. 28, 1975

237,334

PORTABLE BOOK REST AND WORK TABLE OR SIMILAR ARTICLE

Nicholas J. Garofalo, Jr., 259-09 81st Ave.,
Floral Park, N.Y. 11004

Filed Oct. 11, 1973, Ser. No. 405,460

Term of patent 14 years

Int. Cl. D6—06

U.S. Cl. D6—138

FIG. 1 is a perspective view of a portable book rest and work table or similar article, embodying my new design and showing the book rest centrally of the writing table;

FIG. 2 is a perspective view thereof, looking in a direction opposite to that shown in FIG. 1; and

FIG. 3 is a bottom plan view thereof, showing the work table.

I claim:

The ornamental design for a portable book rest and work table or similar article, as shown.
